UNITED STATES PATENT OFFICE.

MILTON TIBBETTS, OF DETROIT, MICHIGAN, ASSIGNOR, BY MESNE ASSIGNMENTS, TO
PACKARD MOTOR CAR COMPANY, OF DETROIT, MICHIGAN, A CORPORATION OF
MICHIGAN.

DESIGN FOR A HANDLE FOR CARRIAGE-DOORS, CASKETS, &c.

41,368.

Specification for Design.

Patented May 9, 1911.

Application filed January 29, 1909. Serial No. 475,085. Term of patent 7 years.

To all whom it may concern:

Be it known that I, MILTON TIBBETTS, a citizen of the United States, residing at Detroit, in the county of Wayne and State of Michigan, have invented a new, original, and ornamental Design for Handles for Carriage-Doors, Caskets, &c., of which the following is a specification, reference being had to the accompanying drawing, forming part thereof.

In the drawing the figure is a plan view of a handle showing my design.

The handle is made up of a straight rounded gripping portion, the ends of which are bent at an angle of about 45° , and are

joined to the upwardly extending side rods which are rounded in cross section and are inclined slightly toward each other. These rods join at their upper ends a cross piece having the peculiar shape shown including the central upwardly curved portion and the annular ends.

I claim:

The ornamental design for a handle for carriage doors, caskets, etc., as shown and described.

MILTON TIBBETTS.
